US00D747998S

(12) United States Design Patent
Yatsugi-Kang

(10) Patent No.: US D747,998 S
(45) Date of Patent: * Jan. 26, 2016

(54) NECKLACE

(71) Applicant: HARRY WINSTON SA,
Plan-les-Ouates (CH)

(72) Inventor: Rie Yatsugi-Kang, Cresskill, NJ (US)

(73) Assignee: HARRY WINSTON SA,
Plan-les-Ouates (CH)

() Term: 14 Years

(21) Appl. No.: 29/510,014

(22) Filed: Nov. 24, 2014

(30) Foreign Application Priority Data

May 22, 2014 (WO) DM/083 634

(51) LOC (10) Cl. 11-01

(52) U.S. Cl.
USPC D11/7
